(57) **CLAIM**

The ornamental design for a wearable device for physiolog-
ical monitoring, as shown and described.

DESCRIPTION

FIG. 1 is a top perspective view of the wearable device for

physiological monitoring embodying our new design;

FIG. 2 is another top perspective view thereof;

FIG. 3 is a bottom perspective view thereof;

FIG. 4 is another bottom perspective view thereof;

FIG. 5 is a front view thereof;

FIG. 6 is a rear view thereof;

FIG. 7 is a top view thereof;

FIG. 8 is a bottom view thereof;

FIG. 9 is a side view thereof; and,

FIG. 10 is another side view thereof.

The broken lines of substantially equal length depict por-
tions of the wearable device for physiological monitoring
that form no part of the claimed design.
